(57) CLAIM

The ornamental design for a portable wireless speaker, as shown and described.

DESCRIPTION

FIG. 1 is a front, top and right side perspective view of a portable wireless speaker showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines shown are included for the purpose of illustrating portions of the portable wireless speaker that form no part of the claim.
